UNITED STATES PATENT OFFICE.

SOREN HANSSON, OF BUTLER, PENNSYLVANIA, ASSIGNOR OF ONE-HALF TO HARRY T. ANDERSON, OF BUTLER, PENNSYLVANIA.

BRAKE-ROD JAW.

Application filed July 24, 1923. Serial No. 653,580.

To all whom it may concern:

Be it known that I, SOREN HANSSON, a citizen of the United States, and resident of Butler, in the county of Butler and State 5 of Pennsylvania, have invented a new and useful Improvement in Brake-Rod Jaws; and I do hereby declare the following to be a full, clear, and exact description thereof.

My invention relates to brake rod jaws for 10 the brake-rigging of railway cars, and one of its objects is to provide an improved jaw formed from a single piece of flat stock and provided with simple and effective means for attaching the jaw to the brake-rod.

15 Another object of my invention is to provide a novel and effective method of making brake-rod jaws of the character indicated above.

In the accompanying drawing, Fig. 1 is 20 a plan view of the end of a brake-rod provided with a jaw attachment constructed according to my invention; Fig. 2 is a side elevational view of the same construction; Fig. 3 is a transverse sectional view taken 25 substantially on the line 3—3, Fig. 2; Fig. 4 is a plan view of a blank suitable for forming the brake-rod jaw shown in Figs. 1 to 3; Fig. 5 is an edge view of the blank shown in Fig. 4; Fig. 6 is a plan view showing the 30 same blank after the stamping operation; Fig. 7 is an end view of the blank as seen from the right of Fig. 6; Fig. 8 is a plan view showing the blank after the bending operation; Fig. 9 is a side view as seen from 35 the top of Fig. 8; Fig. 10 is another side view similar to Fig. 9, showing the central portions of the flanges compressed together; Fig. 11 is a side view similar to Fig. 10 showing the straps or wings bent for engagement 40 to the brake-rod hook, and Fig. 12 is a sectional view similar to Fig. 3 showing the device of Fig. 11 in place within a brake-rod hook before the wings have been bent into the position shown in Fig. 3.

45 In the drawing, the numeral 2 indicates a brake rod having its end bent back upon itself to form a hook 3, to which is secured a jaw member consisting of a U-shaped body portion 4 having opposed openings 5 near 50 its free ends and having flanges formed on its edges. These flanges taper from points adjacent to the openings 5 toward the closed end of the U-shaped jaw member. The portions 7 of the flanges 6 are pressed together 55 and engage each other on the line 8, the

parts being so proportioned that the loop at the closed end of the jaw is of proper size to fit within the hook which is formed on the brake-rod 2. Two straps or wings 9 and 10 are formed integral with the jaw member and are connected to one of the flanged portions 7 by means of a web 11. When the jaw is attached to the brake-rod hook the strap 9 is wrapped around the brake-rod while the strap 10 is wrapped around the hook portion 3 as best shown in Fig. 3. After the jaw member has been slipped into the hook of the brake-rod and the straps have been bent in the manner just described, the end of the hook portion 3 is bent down into the position shown at 12, Fig. 2, thus preventing the jaw attachment from moving lengthwise with respect to the brake-rod.

The several steps in which the jaw member is made are shown in section in Figs. 4 to 11. Figs. 4 and 5 show a blank stamped from flat stock and having a body portion 13 to which the strap portions 9 and 10 are attached by means of the web 11 as in the 70 finished device.

Fig. 6 shows the next operation wherein the body portion 13 of the blank is provided near its ends with openings 14 surrounded by flanges 15, and is also provided at its edges with tapered flanges 6. These flanges taper upwardly toward the center of the blank and are joined by the straight flange portion 7. This operation brings the wing members 9 and 10 to a position nearly perpendicular to the body portion of the blank as best shown in Fig. 7. The dies which form the openings 14 leave a thin layer of metal extending across each opening as shown at 16, Fig. 8. These thin pieces may be punched out before the next operation or at any later time, as may be found most convenient.

Figs. 8 and 9 also show the appearance of the blank after the bending operation 100 wherein the body portion of the blank is bent into U-shape with the openings 14 opposite to each other. Fig. 10 shows the flange portions 7 pressed together and engaging each other on the line 8, the construction 105 being otherwise the same as in Figs. 8 and 9.

Fig. 11 shows the wings or straps 9 and 10 bent at right angles to their original position, this position of the straps being also shown in Fig. 12.

When the jaw attachment is constructed in this manner, with the straps 9 and 10 in the position shown in Fig. 11, it is slipped in the hook of the brake-rod in the manner shown in Fig. 12, after which the straps 9 and 10 are bent around the lower and upper portions of the brake-rod hook in the manner shown in Fig. 3, and the end of the hook is bent down as shown at 12, Fig. 2.

10 It will be noted that the blank shown in Fig. 4 is shaped into the finished jaw device by the two main operations of stamping and bending, Figs. 6 and 8, followed by the minor operations of compressing the loop flanges, Fig. 10, and bending the straps or wings as shown in Fig. 11. The manufacture of this device is therefore very simple and inexpensive. At the same time, the jaw is very strong and rigid on account of the strengthening flanges 6 and 7, and the straps 9 and 10 secure the jaw firmly to the brake-rod. If for any reason it is desired to remove the jaw from the brake-rod this may be readily done by bending up the end 12 of the hook, unwrapping the straps 9 and 10, and slipping the jaw out of the brake-rod hook.

30 While I have shown and described herein the manner in which I prefer to construct my device, it will be understood that various changes may be made without departing from my invention as set forth in the appended claims.

I claim as my invention:

35 1. The method of making a brake-rod jaw that comprises forming a blank having an elongated body portion and also having an integral strap portion joined to one edge of said body portion, forming openings near the ends of said body portion and also forming flanges on the edges of said body portion, and bending said body portion into U-shape.

40 2. The method of making a brake-rod jaw that comprises forming a blank having an elongated body portion and also having an integral strap portion joined to one edge of said body portion, forming openings near the ends of said body portion, bending said body portion into U-shape, with said flanges on the outside, and bending said strap portions to extend substantially perpendicular to their original position and in opposite directions.

45 3. A brake-rod jaw comprising a U-shaped member having opposed openings formed in its arms and also having integral

strap portions joined to the closed end of said U-shaped member.

50 4. A brake-rod jaw comprising a U-shaped member having openings formed in its arms and having flanges formed on the edges of said arms, said flanges engaging each other at the closed end of said U-shaped member, and a strap portion integral with said U-shaped member and joined to the closed end 65 thereof.

55 5. A brake-rod jaw comprising a U-shaped member having openings formed in its arms and having outwardly extending flanges formed at its edges, said flanges tapering from points adjacent to said openings toward the closed end of said member, and the said flanges engaging each other at the closed end of said member, and a strap member integral with said U-shaped member and 70 having its central portion joined to one of said flanges at the closed end of said U-shaped member.

60 6. A brake-rod jaw comprising a hook formed in the end of a brake-rod, a U-shaped member interconnected with said hook and having openings formed in its arms, and a strap member formed integral with said U-shaped member and having its central portion joined to the closed end of said U-shaped member, the ends of said straps being wrapped 75 around the opposite sides of said hook.

65 7. A brake-rod jaw comprising a hook formed in the end of the brake-rod, and having substantially parallel spaced portions, a U-shaped member having its closed end received in said hook, said U-shaped member having openings formed in its arms and having outwardly extending flanges formed at its edges, said flanges tapering 80 from points adjacent to said openings toward the closed end of said U-shaped member, and said flanges engaging each other at the closed end of said U-shaped member, and a strap member formed integral with said 85

90 U-shaped member and having its central portion joined to one of said flanges at the closed end of said U-shaped member, the oppositely extending portions of said strap member being wrapped around said spaced portions 95 of said hook and the end of said hook beyond said strap portions being bent to prevent said strap portions from moving lengthwise with respect to said brake-rod.

100 In testimony whereof I, the said SOREN HANSSON, have hereunto set my hand.

110 SOREN HANSSON.
